DESIGN FOR AN AIR CONDITIONING CONTROL CASING

Earnest J. Dillman, Detroit, Mich.

Application February 28, 1936, Serial No. 61,401

Term of patent 14 years

To all whom it may concern:

Be it known that I, Earnest J. Dillman, a citizen of the United States, residing in the city of Detroit, county of Wayne, and State of Michigan, have invented a new, original, and ornamental Design for an Air Conditioning Control Casing, of which the following is a specification, reference being had to the accompanying drawing, forming part thereof.

Figure 1 is a front view in elevation of a cas-

ing for an air conditioning control, showing my new design;

Fig. 2 is a side view of the casing;

Fig. 3 is a top plan view of the casing, and

Fig. 4 is a perspective view of the casing.

I claim:

The ornamental design for an air conditioning control casing, substantially as shown.

EARNEST J. DILLMAN.
